VESTIBULE CLOSURE FOR RAILWAY CARS

Ethan I. Dodds, Jr., Central Valley, N. Y., assignor
to The New York Central Railroad Company, a
corporation of New York

Application May 29, 1936, Serial No. 82,662

9 Claims. (CL. 105—8)

This invention relates to vestibule closures for closing the space between the vestibules of two adjacent passenger cars, the principal object of the invention being to provide closures, particularly for the ends of cars of a non-articulated passenger train, which will present a smooth continuous connection giving a flush exterior surface or streamline contour between cars conforming with the outer contour of the car bodies and at the same time allowing all requisite movements of the closure elements to compensate for car end movements without undue wear and tear upon the closure elements while giving increased and adequate protection against the entrance of rain, snow, dirt and cinders into the vestibules or passageways between cars.

One of the most important features of streamlining a passenger train is the closing of openings between adjacent cars in such a way as to provide a continuous flush exterior surface, eliminating all projections and pockets, to reduce wind resistance and produce an appearance of continuous construction from end to end of the train.

In the case of an articulated train, where the ends of two adjacent cars are carried on the same truck, this does not present any serious problem, as the relative movements between car ends is limited and it is generally customary and sufficient practice to apply sheet rubber or other flexible material over the opening and firmly attached to the ends of the car, relying upon the elasticity of the rubber or other fabric used to compensate for car movements on curves.

In the case of a non-articulated framing, closing the spaces between cars to accomplish the desired results, represents a much more difficult problem on account of the increased relative movements between the ends of adjacent cars due to draft gear and buffer actions, curvatures of track, offsets when taking curves and switches and vertical oscillations. Various methods of taking care of this condition have been developed and are in actual operation, some of which are apparently satisfactory to a certain degree. In most instances, however, the elasticity of a fabric covering of some sort is relied upon, at least to some extent, to maintain a flush exterior surface under various operating conditions, and this type of construction can not be expected to give satisfactory service over an extended period due to the rapid deterioration of the fabric under the severe conditions. Some of the various closures which have been used are of metal shield type requiring an objectionable amount of installation space, or have been constructed with folds pre-

senting an accordion appearance between cars, or have been constructed of elastic material requiring in its operation stretching beyond its elastic limit, or have been made of contour curtains requiring a complex arrangement of pulleys, springs and guide rods preventing either a durable or a satisfactory type of streamline contour being obtained.

The present invention provides a metal shield and fabric type of closure construction which eliminates the foregoing and other known objections to prior constructions and efficiently solves the problem of closing the spaces between the vestibule ends of non-articulated cars in an all round satisfactory manner. The present invention also provides a closure construction which avoids the production of clashing or other objectionable noises in the working action of its parts.

The invention consists of the features of construction, combination and arrangement of parts, hereinafter fully described and claimed, reference being had to the accompanying drawings, in which:

Fig. 1 is a side elevation showing coupled cars of a passenger train embodying the invention. 25

Fig. 2 is a similar view on an enlarged scale of adjoining ends of two passenger cars embodying the invention.

Fig. 3 is an end elevation of a car showing the closure structure partially broken away to expose certain normally concealed parts. 30

Fig. 4 is a view similar to Fig. 3, on an enlarged scale, of a car end on one side of its longitudinal center showing in dotted lines the parts disposed between the frame members of the closure and concealed by the outer frame member. 35

Fig. 5 is a central vertical section on the line 5—5 of Fig. 4.

Fig. 6 is an enlarged central section through the upper portion of a car end, the closure frames and the upper central suspension stem. 40

Fig. 7 is a horizontal section on the line 7—7 of Fig. 4.

Fig. 8 is a horizontal section on such a plane as that indicated by line 8—8 of Fig. 3 through two abutting car ends. 45

Fig. 9 is a horizontal section similar to Fig. 7 showing a wide end post construction.

Fig. 10 is a view similar to Fig. 9 showing the invention as applied to the stub end of a car. 50

Fig. 11 is a rear elevation of a portion of a tender showing the application of the invention thereto.

Fig. 12 is a central vertical section on line 12—12 of Fig. 11. 55

Fig. 13 is a view similar to Fig. 7 showing an extreme angular arrangement the closure frames may assume in a swiveling movement of car ends.

5 Fig. 14 is a horizontal section showing a modified construction of bottom center stem and side stems.

Figs. 15 and 16 are sections taken, respectively, on lines 15—15 and 16—16 of Fig. 14.

10 Referring now more particularly to the drawings, 1 designates cars of a streamlined passenger train each provided with a vestibuled end 2 having side doors 3, and each car also preferably having its side walls and doors provided with 15 pending skirts 4 partially covering its running gear to give as far as possible a streamline surface to such portion of the car for reduction of air resistance. The vestibuled ends 2 of the cars are further provided with buffer type closures 20 5 constructed in accordance with my invention, the closures at the ends of adjacent cars being arranged to abut to snugly close the openings therebetween so as to make the side and roof surfaces of all the cars of a train substantially 25 continuous or flush from end to end of the train to give a streamline effect and pleasing appearance to the train as a whole and whereby air resistance to travel is still further reduced.

30 The outer end wall 6 at each end of the car 30 includes posts 7 forming the sides of the passageway 8 leading to and from the vestibule space 9, and at the angle of intersection of the wall 6 with the roof 10 and sides 11 of the car is provided a flange-like projection 12 which is flush 35 with the roof and sides and extends a short distance outwardly beyond the wall 6 to form a recess 13 at the end of the car. Secured at spaced intervals to the flange 10 and adjacent portions of the wall 6 within this recess are cushioning 40 pads or bumpers 14 of rubber or other suitable durable cushioning and sound deadening material. On the outer side faces of the outwardly projecting portions of the posts 7 are provided cushioning, wear sustaining and sound reducing 45 blocks or pads 15.

Each end closure comprises an outer frame member 16 and an inner frame member 17, each of which is of generally similar outline form and corresponding to the outline form of the end of 50 the car. Each frame member 16 and 17 is generally of inverted U-shape and comprises a frame part proper embodying side posts or legs 18 connected at their upper ends by a cross rail portion 19. The outer frame member further comprises sill and lintel pieces 20 and 21 connecting the legs 18 at proper heights, inner post members 22 extending between the parts 20 and 21, cross braces or guards 23 connecting the legs 18 and post 22 at different elevations, and a transom 60 plate or piece 24 filling the space between the rail 19, adjacent portions of the legs 18 and the lintel 21. The parts 20, 21 and 22 of the frame member 16 form a passageway alining with the passageway 8 of the vestibule end. The similar 65 parts of the frame members are of channeled formation and the channels of the frame member 16 face inwardly, while the channels of the frame member 17 face outwardly, the outer faces of the portions of the frame member 16 of the 70 closure on each car being arranged in a common plane to form an abutment surface for engagement with the abutment surface of the corresponding frame member of the closure on the end of an adjacent car when two cars are coupled together.

The outer frame member 16 is supported from the end of the car to take care of vertical oscillations, movements toward and from the end of the car to compensate for draft gear and buffing actions, and angular swinging movements relative to the end of the car about a vertical center as an axis of motion to compensate for swiveling movements incident to travel of the car around curves, etc. To this end, the frame member 16 is supported from the car end 6 by a three-point 10 suspension providing an upper central buffer stem or bolt 25 and a pair of lower buffer stems or bolts 26. The upper buffer stem or bolt 25 slidably engages a bearing member or housing 27 on the wall 6 above the passageway 8 and is provided at its outer end with a ball head 28 engaging a split bearing member 29 on the transom portion 24 of the frame member 16, a coiled compression spring 30 being arranged between the housing and bearing to normally hold the member 16 pressed away from the wall 6 and cooperating with the bolt or stem 25 in its sliding movements to permit the member 6 to have buffing movements toward and from the wall 6. A nut 31 applied to the inner end of the stem or bolt limits its outward movement and prevents its displacement. The ball and socket connection 28 and 29 permits the section 6 to have a restricted degree of movement in a vertical plane 30 to take care of vertical oscillations and a wide degree of tilting motions vertically and laterally to compensate for other car motions. Each lower buffer stem or bolt 26 is slidably mounted for movement longitudinally of the car in bearings 35 on the platform casting 32 and adjacent parts of the car underframe and is coupled at its forward end to the sill piece 20 of the frame member 16, which forms a buffer face plate casting, by a pivot bolt 33. A nut 34 applied to the inner end of the bolt or stem limits its outward movement and a coiled compression spring 35 disposed about the bolt or stem between bearing parts normally holds the bolt or stem and the member 16 pressed outwardly and permits elastic inward 40 and outward movement of the bolt or stem and member 16 for cushioned buffing actions. The three suspension members 25 and 26 so constructed and arranged also permit the member 16 to swing on the member 25 as a vertical axis of motion to adapt them to assume different angular positions between car ends to compensate for relative movements between ends of adjacent cars due to offsets when taking curves and switches, as will be readily understood.

The frame member 16 is also supported at each side of its vertical center from the car end 6 by elastic suspension devices or hangers 36, each comprising a rod member 37 jointed or pivotally connected at its upper end, as at 38, to the wall 6 and slidably and pivotally engaged at its lower or free end by a yoke member 39. The yoke members 39 of the suspension devices are fitted in the channels of the posts 22 of the frame member 16 and coupled at their lower ends by bolts 40 to the sill or buffer casting piece 20. The lower ends of the rods 37 are provided with nuts 41 engaging abutments 42 slidable on the yokes and between which and the upper ends of the yokes are arranged compression springs 43 elastically connecting the rods and yokes for relatively sliding movements. The devices 36 assist in sustaining the weight of the frame member and closure 5 as a whole and to relieve the suspension members from the support of an undue amount of such weight and to prevent possible 75

binding movements thereof, while not interposing any restrictions to the buffing and car motion compensating movements of the closure.

The inner closure frame member 17 is a floating frame member, i. e., is supported wholly by the frame member 16 and not in any manner, except through the member 16, from the car. It, the member 17, is yieldingly supported at each side by counterbalancing and suspension devices 44 extending at an inward and downward or diagonal angle between the legs 18 of said frame members. Each suspension device comprises rod sections 44 and 45 connected by a turnbuckle 46 and a compression coil spring 47, one of which rod sections may include parts suitably jointed to allow flexibility. The supporting action of these suspension devices 44 is supplemented by the torsional resistance of full elliptical springs 48, five in number, two at each side at different elevations between the frame legs 18 and one at the top centrally of and between the transoms 24 of the frame members. The opposed leaves of these springs are fixed to the frame members 16 and 17 within the channels of the legs and 25 said springs serve as buffing springs to normally hold the frame members 16 and 17 expanded or spread apart and to allow collapsing movement of the section 16 toward the section 17 and relative angular movements of said sections. Any 30 over stress of the weight of the section 17 on the springs 48 is prevented wholly or in part by the suspension devices 44 so as to ensure freedom of movement of the springs 48 and to avoid any binding action thereof. In addition, outwardly 35 and downwardly angled or diagonally arranged stabilizers 49 connect the posts 22 of the frame member 16 with the legs 18 of the frame member 17. Each of these stabilizers comprises a cylinder 50 pivoted to the frame member 16 and a rod 51 pivoted at one end to the frame member 17, the opposite end of the rod being fixed to a piston 52 movable in the cylinder and acted upon by a compression spring 53 which allows elastic elongation and contraction of the stabilizer to a 45 specified degree. The stabilizers further assist in supporting the frame member 17 from the frame member 16 and counteract any tendency to independent side sway or lateral vibration of the frame member under violent side swaying 50 movements of the cars.

The space between the outer and inner frame members at the top and sides thereof is closed by a cover sheet 54 of some suitable durable elastic fabric material, which is normally held taut by the pressure of the springs in the normal or spread condition of the frame members 16 and 17, this elastic covering serving to provide a closure for the openings which is substantially flush with the roof and side walls of the car and 60 thus, when the closures of two coupled cars are in abutting relation, will maintain a continuity of surfaces and close the gap between the ends of the car. These flexible coverings also, to a very large extent, exclude rain, snow, cinders and dust from getting access to the spaces between the closures and car ends and finding their way through the passageways 8 into the vestibules and passenger compartments of the car, while at the same time allowing free and unimpeded 65 movement of the frame members 16 and 17 in their car motion compensating movements with relation to each other. The surfaces of the frame member 17 and the portions 18 and 19 of the frame members 16 are adapted in their movements to engage the cushioning pads or blocks 70 oscillations and such angularities of movement,

14 and 15 in their relative inward and outward movements to reduce wear and tear by rubbing contact between the surfaces, to further assist in preventing entrance of rain, snow, cinders, dust and other foreign particles and to prevent noises which would otherwise arise as a result of chafing contact of the parts with one another. In order to further close the openings between the abutting closure members at the adjacent ends of coupled cars, curtains 55 of a suitable durable and flexible material are provided to close the spaces at the sides of the passageway between the adjacent thresholds of the passenger spaces 8, each curtain being mounted to wind upon and unwind from a spring roll 56 and provided at its free edge with a retaining ring or like holding device 57. The arrangement is such that the roll 56 of one curtain is mounted in bearings upon the post 7 at one side of the passageway 8 of one car, while the curtain roll 56 of the other curtain is mounted upon the post 7 at the opposite side of the passageway 8 of the other car, and retaining hooks 58 are provided upon a remaining post 7 for engagement of the retaining rings 57 therewith whereby the curtains may be held withdrawn from the spring rolls to close the spaces at the sides of the passageways between the adjacent cars across the post 22 of the outer frame members 17 of the respective closures. By this construction and arrangement it will be seen that these spaces will be completely closed while in the swiveling movements of the cars, in which the members of the closures 5 upon the respective cars assume different angles of position with relation to each other in making right and left hand turns, one curtain may wind and the other unwind to permit of such movements without uncovering the openings and without injury to or disruptive strain upon the curtains. In order to maintain the streamline surfacing of the closures 5 below the floor level of the cars the legs 18 of the frame members are prolonged or extended below the sill pieces 20, as at 59, to the level of the lower edges of the skirts 4 so that all vertical surfaces of the closure members will lie flush with the side walls and their skirts between the ends of the cars. This construction is permitted by the use upon the cars, in conjunction with automatically closing draft couplers 60, of automatic tight lock coupling and uncoupling fluid line couplers 61, which obviate the necessity of leaving the spaces closed by the leg extensions 59 partially or wholly open in order that hand uncoupling levers or devices may be reached and manipulated.

It will be evident from the foregoing description that when the adjacent ends of two cars provided with closures 5 embodying my invention are coupled together and the curtains 55 thereof are drawn out and secured in operative position the space between the ends of the cars will be closed at top and sides by a closure construction conforming in contour to the roof and sides of the car and in such manner as to provide a continuously flush exterior surface, eliminating all projections and pockets to reduce wind resistance and that this arrangement throughout all the cars of a train will produce a pleasing streamline conformation and appearance from end to end of the train. These closures 5 also are of compact type and readily fit within the conventional space and are relatively movable for cushioned buffing actions to compensate for endwise movements allowed by couplers, as well as vertical 75 movements and such angularities of movement,

without clashing or binding, as are necessary to compensate for offsets and all other relative movements of the cars in taking curves, switches, etc. In such movements the flexible cover sections 54 may fold and straighten out and the curtains 55 may wind and unwind to keep exposed portions covered without undue wear and tear upon these parts. The closure structures in addition to closing the gaps between cars to give 10 a continuous streamline contour throughout the length of the train also serve to exclude rain, snow, cinders and dust, whereby the vestibules are kept in a more cleanly condition and greater comfort and convenience to passengers ensured. 15 Furthermore, as the closures are formed of telescoping frame members which are yieldingly supported relative to the car and to each other and accurately guided, cushioned controlled in their yielding movements liability of jamming and injury to the parts is avoided and an easy working 20 action of the same secured.

The buffing or abutment surfaces of the frame members 16 and 17 are adapted, as stated, to contact with the rubber or other resilient or 25 flexible buffers 14 and 15 in order to reduce wear and prevent clashing or binding contact of the parts producing any objectionable noise. In a buffing movement, the frame section 22 moves inwardly until the frame member 17 engages the 30 end wall 6, whereby further inward movement of the section 17 is prevented, after which the section 16 may continue to move inwardly against the resistance of the elliptical cushioning springs, the rubber or other fabric covering 54 folding 35 and remaining in this position until normal conditions are restored and the pressure on the springs is relieved by separation of the frame member 17 from contact with the car end and by outward movement of the frame section 16, 40 the curtains winding and unwinding in these movements. In this operation, the fabric coverings and curtains are not subjected to any stretching or tension except that due to slight initial pressure exerted by the elliptical springs 45 in maintaining the fabric taut under all conditions of normal main line operation. When the closure frames swing and shift to an angular position with relation to the car ends, as when the cars are rounding a curve, the fabric covering at one side is folded while that at the opposite side may be extended or stretched to some degree in an extreme extent of movement, but not to an excessive degree, or beyond its elastic strength, and hence durability of the fabric coverings is ensured, while at the same time a 50 streamline arrangement of the fabric coverings is maintained under all normal conditions. The capability of the support in expanding and contracting and at the same time swinging to different angular positions ensures ease of motion of the parts of the closure to accommodate all car movements without throwing excessive strain upon any of the parts of the closure.

If desired, a center stem 62, either fixedly or 65 yieldingly mounted, may be provided upon the buffer plate casting 32 and car underframe for coaction with the sill piece or buffer face plate casting 20 of the frame member 16 to form a lower pivotal connection between the closure and 70 car end on which the closure may swing laterally as a bottom fulcrum support, the upper portion of the closure swinging on the ball and socket connection 28-29 of the stem 25 as an upper fulcrum support arranged in vertical alignment 75 with the stem 62. The stem 62 has an outer

rounded end 63 to seat within a pocket or recess 64 in the buffer face plate 20 of the frame member 16, through which engagement a pivotal connection is furnished and this engagement may be to a sufficient degree to adapt the stem 62 5 to serve as an added support sustaining member. As shown in Figs. 14, 15, and 16, the lower buffer stems 26 instead of being connected at their outer ends to the plate casting 20, as in the case of the buffer stems 26 previously described, 10 may be provided with ball heads 65 engaging sockets 66 on the plate casting 20, and the stem 62' may be provided with a spherical end 63' to seat within a correspondingly shaped recess 64' in the plate casting 20, to secure greater freedom 15 of action of the frame member 16, without liability of binding, at these points.

The foregoing description applies to the construction of the closure per se and mode of mounting the same on the vestibuled ends of 20 cars, and particularly those having vestibules of narrow post type, i. e., in which the posts 7 are spaced to form a narrow passageway 8. Suitable changes in the structure, of course, are or may be made in applying the closure to cars having 25 vestibules of wide post type, i. e., spaced a greater distance apart than those of narrow post type. Fig. 9 shows a modification designed for a vestibule end of wide post type, in which 7 represents 30 one of the posts, 8' the passageway, 9' the vestibule space, and 16' and 17' respectively the frame members of the closure. In this construction the posts 22' of the frame member 16', and the corresponding posts (not shown) of the frame member are spaced a distance apart to suit the spacing 35 of the posts 7' and each post 7' has attached thereto an outwardly extending guide plate 67 which is adapted to be overlapped by a guide extension 68 from the post 22' of the frame member 16'. The end of the plate 67 which is fastened 40 to the post 7' is formed to provide with an angle plate 69 a housing for the curtain roll 56' mounted in bearings on the post body 7'. This angle plate forms a door for the housing which is hinged on the post, as at 70, to swing open and closed 45 to permit access to the roll when desired and to form a closure flush when in closed position with the guide plate 67. The hinged end of the plate 69 carries a cam member 71 engageable with a leaf spring 72 on the post to frictionally hold or 50 lock the plate 69 in either its opened or closed position and against accidentally opening when in closed position. The curtain 55' here is adapted when drawn out to move in guided contact with the extension plate 67.

In the application of the invention as shown 55 in Fig. 10 to the stub end of a car, such as a combination baggage and passenger car 16a, the general construction of the parts may be the same as that previously described except with regard 60 to the omission of curtains and such changes in details as are necessary to mount the closure upon the blind end wall 6a. In Fig. 10, 16a is the outer frame member and 17a the inner frame member, both of which are the same in general construction as the frame members 16 and 17 except that the openings between the legs of the frame member 16a may be wholly or partially closed by cover sheets 73. On the frame member at each side of the car 16a may be provided a step 74 and one 70 or more hand grips 75 to take the place of those usually provided on the end wall. The buffer stems 25 and 26 in this construction pass through wear plates 89 at the points where they 75 pass through the platform casting and have

heads 30 engaging seats in the wear plates. Between the seat 33 and nuts 34 at the outer end of each stem is a spring 30' to supplement the cushioning action of spring 30 or spring 35 as the case may be and to minimize rattling at this point.

In the application of the invention to the rear end of the locomotive tender, as shown in Fig. 11, the tender 1a is provided with a false end wall 16 beyond the rear wall proper 6b, and the outer frame member 16b of the closure carrying the inner frame member 17b is supported at its upper end from this false wall 16 by the suspension devices 36 and the top center stem 25 as previously described, but in place of the use of the sliding lower buffer stems 26 spring buffers 26a are employed. Each of these consists of a cylinder 77 fixed to the buffer beam 18, a hollow plunger 79 movable in the cylinder and a coiled compression spring 80 arranged in the cylinder and plunger and operating to cushion the inward movements of the latter, the plunger being pivoted to the sill or buffer plate 20b of the frame member 16b. The plate 20b carries a step plate section 81 slideable under a coacting step plate section 82 at the lower end of a riser uniting it to the foot plate 83 leading to the ladder 84. The frame member 16b here abuts against the similar frame member on the stub or blind end of the first or following car of the train, as will be readily understood, to close the gap therebetween. The frame member 16b may be provided with a step 74 and one or more hand grips 75 as in the construction shown in Fig. 10.

35 The buffer castings 20 may be provided under their tread plate or floor portions with L-shaped face plates 87 bolted thereto and which carry the pivot brackets or bearings for the outer ends of the buffer stems 26. These parts are removable to allow ready removal of the buffer stems. Contact lugs 88 may be provided on the buffer castings to limit the inward travel of the frame members 16 and obviate any liability of crushing frail parts under compression in extreme buffing actions.

45 The ball joint of the upper buffer center stem 25 is designed to permit the buffer closure to swivel and move back and forth without rattling and to permit worn parts to be readily removed. 50 As shown its bearing 29 is fitted in a housing 91 secured to the frame member 16, which housing has an opening through which the center stem and ball joint bushing or bearing 29 may be removed upon removal of a detachable cap 92 normally closing said opening.

55 From the foregoing description, taken in connection with the accompanying drawings, the construction of my improved car and diaphragm or closure for the openings between the ends of 60 cars will be readily understood and its advantages appreciated without a further and extended description. While the constructions shown are preferred, it will, of course, be understood that changes in the construction, form and proportions 65 of the parts may be made within the scope of the appended claims without departing from the spirit or sacrificing any of the advantages of the invention.

70 What I claim is:—

70 1. A car end diaphragm or closure for the space between adjacent ends of coupled cars comprising outer and inner inverted U-shaped diaphragm sections, means for supporting the outer section on the car for pivotal movements 75 on a central vertical axis and for buffing move-

ments toward and from the car, means for cushioning the buffing movements of said outer section, and supporting and buffing means yieldably supporting the inner section from the outer section. 5

2. A car end diaphragm or closure for the space between adjacent ends of coupled cars comprising outer and inner sections, means for yieldably suspending the outer section from the car, means for supporting the outer section from the car for pivotal movements on a central vertical axis and for buffing movements toward and from the car, means for cushioning the buffing movements of said outer section, and supporting and buffing means yieldably supporting the inner section from the outer section. 10 15

3. A car end diaphragm or closure for the space between adjacent ends of coupled cars comprising outer and inner inverted U-shaped diaphragm sections, means arranged centrally at the top of the outer section and on opposite sides of the vertical center of said outer section for supporting the outer section on the car for pivotal movements on a central vertical axis and for buffing movements toward and from the car, means for cushioning the buffing movements of said outer section, and supporting and buffing means yieldably supporting the inner section from the outer section. 20 25

4. A car end diaphragm or closure for the space between adjacent ends of coupled cars comprising outer and inner inverted U-shaped diaphragm sections, means yieldably suspending the outer section from the car, means for supporting the outer section on the car for pivotal movements on a central vertical axis and for buffing movements toward and from the car, means for cushioning the buffing movements of said outer section, and supporting and buffing means yieldably supporting the inner section from the outer section. 30 35 40

5. A car end diaphragm or closure for the space between adjacent ends of coupled cars comprising outer and inner inverted U-shaped diaphragm sections, means for supporting the outer section on the car for pivotal movements on a central vertical axis and for buffing movements toward and from the car, means for cushioning the buffing movements of said outer section, spring means supporting the inner section from the outer section and adapted to permit elastic collapsing and expanding movements between said sections, and stabilizers connecting the inner section with the outer frame to elastically restrict independent play of the inner section from the outer section. 45 50 55

6. A car end diaphragm or closure for the space between adjacent ends of coupled cars comprising outer and inner inverted U-shaped diaphragm sections, means for supporting the outer section on the car for pivotal movements on a central vertical axis and for buffing movements toward and from the car, means for cushioning the buffing movements of said outer section, spring means supporting the inner section from the outer section and adapted to permit elastic collapsing and expanding movements between said sections, elastic suspension connections between said sections to partly relieve the elastic means from the load weight of the inner section, 60 and stabilizers connecting the inner section with the outer frame to elastically restrict independent play of the inner section from the outer section. 65 70

7. A car end diaphragm or closure for the 75

space between adjacent ends of coupled cars comprising outer and inner inverted U-shaped diaphragm sections, means yieldingly suspending the outer section from the car, means for supporting the outer section on the car for pivotal movements on a central vertical axis and for buffering movements toward and from the car, means for cushioning the buffering movements of said outer section, spring means supporting the inner section from the outer section and adapted to permit elastic collapsing and expanding movements between said sections, elastic suspension connections between said sections to partly relieve the elastic means from the load weight of the inner section, and stabilizers connecting the inner section with the outer frame to elastically restrict independent play of the inner section from the outer section.

8. A car end diaphragm or closure for the space between adjacent ends of coupled cars comprising outer and inner collapsible sections each formed of an inverted U-shaped channeled frame, the frames having their channels facing each other, and the frame of the outer section being provided with posts forming the sides of a passageway, means for yieldingly suspending the outer section from the car end, means for supporting the outer section from the car end for pivotal movements on a central ver-

tical axis and for cushioned buffering movements toward and from the car, spring means yieldably supporting the inner section from the outer section, and means connecting the inner section with the outer section for assisting said spring means in sustaining the vertical load weight of the inner section. 5

9. A car end diaphragm or closure for the space between adjacent ends of coupled cars comprising outer and inner collapsible sections 10 each formed of an inverted U-shaped channeled frame, the frames having their channels facing each other, and the frame of the outer section being provided with posts forming the sides of a passageway, means for supporting the outer section from the car end for pivotal movements on a central vertical axis and for cushioned buffering movements toward and from the car, spring means yieldably supporting the inner section from the outer section, means connecting the 20 inner section with the outer section for assisting said spring means in sustaining the vertical load weight of the inner section, and stabilizing means connecting the inner section with the outer section for limiting the play of the inner 25 section under car vibrations with respect to the outer section. 15
